HYDROGENATION PROCESS

Bernard S. Greensfelder, Oakland, and Walter H. Peterson, Berkeley, Calif., assignors to Shell Development Company, San Francisco, Calif., a corporation of Delaware

No Drawing. Application May 9, 1944,
Serial No. 534,807

7 Claims. (Cl. 260—683)

1

This invention relates to the controlled partial saturation of unsaturated organic compounds having a plurality of double bonds in the molecule. It deals particularly with the conversion of aliphatic or alicyclic polyolefinic compounds to olefinic compounds having fewer olefinic linkages, especially their conversion to the corresponding mono-olefinic compound.

The hydrogenation of polyolefinic compounds such as diolefins to the corresponding mono-olefinic compound is rendered difficult by the tendency of the reaction to continue beyond the mono-olefin stage with resulting production of undesired completely saturated products. Attempts to eliminate such undesired reaction in the past have not been satisfactory. Thus, for example, it has been proposed to reduce the formation of paraffins in hydrogenating polyolefins to mono-olefins by limiting the proportion of hydrogen to the stoichiometric requirement for the production of mono-olefins or to even lower proportions. However, this leads not only to incomplete hydrogenation of the polyolefins to mono-olefins but also favors polymerization and the consequent deposition of higher boiling products on the catalyst greatly reducing its effective life. Furthermore, even with such low hydrogen ratios the formation of saturated products has been by no means completely suppressed.

It is an important object of the present invention to eliminate the foregoing and other defects of previous methods for the partial hydrogenation of organic compounds having at least four unsaturated carbon atoms in a non-aromatic group. Another object is to provide an efficient, economical and commercially practical method for converting polyolefinic compounds to mono-olefinic compounds with minimum formation of saturated products. A further object is to selectively convert the diolefinic content of hydrocarbon mixtures, such, for example, as the products of thermal or catalytic cracking and the like containing diolefins and mono-olefins, to mono-olefins without substantially reducing the total olefin content thereof. Still other objects and advantages of the invention will be apparent from the following description of the new selective hydrogenation process.

In the interest of clarity, the invention will be described with more particular reference to its application to the production of mono-olefins from hydrocarbon mixtures containing diolefins, particularly conjugated diolefins, and the corresponding mono-olefins because this type of operation presents special difficulties due to the tendency of such diolefins to polymerize and interfere with the desired hydrogenation. However, this application of the process is intended to be illustrative only and it will be understood that the invention is not limited to the treatment of con-

2

jugated diolefins nor with respect to the source or nature of the unsaturated compound treated or of any other components which may be present therewith and that, by proper adjustment of operating conditions, the invention may be applied to the selective hydrogenation of other unsaturated compounds having at least four unsaturated carbon atoms in a non-aromatic group.

It has now been found, and the invention is based upon the discovery, that the hydrogenation of diolefins can be carried out so as to produce mono-olefins with minimum formation of completely saturated products provided a special type of catalyst is used to promote the reaction and excessive reaction times are avoided. A wide variety of catalysts, particularly the various metals of groups 6, 7 and 8 of the periodic system such as tungsten, molybdenum, manganese, iron, nickel, cobalt, etc., their sulfides and oxides and combinations thereof, have been proposed for use in divers hydrogenation processes, especially hydrogenations having as an object the production of saturated organic compounds. It was unexpected, therefore, to find that among these many catalytic agents nickel sulfide is unique in the hydrogenation of polyolefinic compounds and that this catalyst is definitely not the equivalent of other hydrogenation catalysts in this reaction but is capable of substantially completely converting polyolefinic compounds into mono-olefinic compounds without substantial formation of saturated products. This highly selective hydrogenation by the use of nickel sulfide of polyolefinic compounds in preference to, and to the substantial exclusion of, hydrogenation of any mono-olefinic compounds present, is very likely associated with selective surface adsorption. But whatever the explanation, it has been found that catalysts having an active agent consisting predominantly of nickel sulfide are markedly superior to other catalysts in their selectivity for the hydrogenation of polyolefins.

Nickel sulfide catalysts for use in the invention may be prepared in a variety of different ways and the particular form which will be most advantageous in any given case will depend, among other things, on the particular processing method. Thus, for operations in the vapor phase with a fixed bed of catalyst, which is the preferred procedure for treating lower boiling polyolefinic compounds or mixtures containing such compounds, the catalyst may be used in the form of relatively coarse aggregates or shapes of, for example, about 2 to 12 mesh. When the hydrogenation is to be carried out with the polyolefinic compound in the liquid phase it is usually more advantageous to use the catalyst in a sufficiently divided condition so that it may be employed as a suspension in the reaction mixture. For reaction by the dust or powdered catalyst meth-

od, for example, in the fluid catalyst system, relatively finely divided catalyst is also desirable.

The nickel sulfide may be used alone, or may be employed in admixture with other suitable materials which may or may not have catalytic or other activity under the reaction conditions. Thus, nickel sulfide in the form of pellets or granules or other shapes which may be obtained by extrusion or molding or other treatment of nickel sulfide with or without binders, stabilizers, activators or other components may be employed. Alternatively the nickel sulfide may be used on supporting material or carriers such as silica, alumina, clays, and the like which may or may not have been previously activated in any suitable manner. One simple, advantageous method of producing very effective catalysts is by reacting ordinary nickel hydrogenation catalysts with hydrogen sulfide. For example, nickel nitrate or nickelous formate may be used to impregnate an alumina or majolica carrier and then decomposed by heating at about 250° C. to 350° C. The resulting nickel oxide is reacted with preheated hydrogen sulfide at about 400° C. until the surface is substantially completely nickel sulfide; about four hours of heating with hydrogen sulfide being usually sufficient. However, as previously indicated, other methods of catalyst preparation may be used.

The selective hydrogenation of polyolefinic compounds to mono-olefinic compounds may be carried out at various pressures and temperatures depending, at least in part, on the particular starting material being treated. Although relatively high pressures may be employed, it is generally preferred, particularly for operations carried out in the vapor phase, to use moderate pressures between atmospheric and about 200 pounds per square inch. With such pressures, temperatures of about 100° C. to 400° C., preferably about 100° C. to about 350° C. may be used. The optimum temperature and pressure combination within these preferred ranges will depend not only on the activity of the catalyst, which may vary with its method of preparation and with its period of use (fresh or newly regenerated catalysts generally requiring less drastic conditions, that is a lower temperature or a lower pressure or both, than catalysts which have been in use for some time), but also on the other operating conditions. For example, a short time of contact of the reactants with the catalyst may require more intense conditions, than when longer contact times are used. Liquid hourly space velocities of about 0.5 to 12 are generally suitable and in any case the reacted hydrocarbon is most advantageously removed from the reaction zone substantially as fast as one molecule of hydrogen per molecule of diolefin is reacted therewith.

In the present process, the ratio of hydrogen

of diolefins without substantial conversion of mono-olefins. However, it is preferred to employ a substantial excess of hydrogen over the stoichiometric requirement for the desired hydrogenation, advantageously at least twice and more preferably 5 to 15 times such requirement is used. It has been found that excess hydrogen of this order has a favorable effect in preventing polymerization and condensation reactions, which otherwise may cause the catalyst to become more rapidly coated with resinous and carbonaceous materials operating to shorten its effective life. However, nickel sulfide catalysts which have thus lost their selectivity or activity may be regenerated by burning off the deposit in a stream of air at a temperature preferably not substantially above about 400° C. This treatment sometimes causes an excessive loss of sulfur from the catalyst with resultant loss of selectivity for the desired diolefin hydrogenation. In such cases the selectivity of the catalyst may be restored by re-treatment with hydrogen sulfide or other sulfurous gases at about 350° C. to about 400° C. until a surface consisting essentially of nickel sulfide is again produced.

It is also advantageous in order to preserve the selectivity of the catalyst during use, to add a small amount of sulfur (for example, as such or preferably as hydrogen sulfide or other sulfurous compounds of sulfur) which serves to maintain the sulfur content of the catalyst. A portion or all of the hydrogen sulfide or the like present in the reactor effluent gases may be recycled, if desired, with the unreacted hydrogen.

The following examples further illustrate the principles of the invention and show in more detail one method of carrying it out. They also indicate the advantages, particularly with respect to selectivity, of the new method of partial hydrogenation of polyolefinic compounds.

Example I

The starting material used for the selective hydrogenation consisted of a C₅ fraction of petroleum cracking products containing pentadienes and amylenes and had the following composition where, due to the inaccuracies inherent in present methods of determining dienes when present in high concentrations, the percentages total 101%.

Dienes	70%	Total olefins 98%
Mono-olefins	28%	
Above C ₅	3%	

This mixture was fed at a liquid hourly space velocity of unity over various nickel sulfide catalysts prepared in different ways using various temperatures, pressures and hydrogen to diene ratios. The following table shows the operating conditions employed and the results obtained.

Catalyst	Temper- ature, ° C.	Pressure, p. s. i. g.	Mol ratio, H ₂ to diene	Analysis of product	
				Olefins, per cent	Dienes, per cent
Nickel sulfide on majolica	320	30	12	98	1.0
Nickel sulfide on 4-mesh alumina	230	30	12	98	1.0
Nickel sulfide on 8-mesh Alcorco grade A alumina	200	40	12	98	1.0
Nickel sulfide on 8-mesh Alcorco grade A alumina	300	0	12	98	1.0
Sulfided nickel on alumina hydrogenation catalyst	250	100	5	98	0.2
Sulfided nickel on alumina hydrogenation catalyst	250	50	3	97	0.0

to the polyolefinic compound or compounds to be hydrogenated may vary within wide limits because of the aforementioned discovery that nickel sulfide catalysts promote selective hydrogenation

These results show that substantially complete conversion of dienes without material production of saturates can be obtained under a wide variety of operating conditions by the use of

nickel sulfide catalysts according to the invention.

Example II

A mixture of normal and iso butanes and butylenes and 1,3-butadiene containing 53.2% total olefins, 15.8% isobutylene and 10.9% butadiene was submitted to selective hydrogenation in the presence of nickel sulfide catalyst, under the conditions and with the results shown below:

Temper- ature, °C.	Pressure, p. s. i. g.	Feed rate, L. H. S. V.	Mol ratio, H ₂ to diene	Analysis of product		
				Total olefins, per cent	Tertiary olefins, per cent	Dienes, per cent
175.....	100	0.9	6.8	.....	.....	0.38
198.....	100	2.0	6.4	.....	.....	0.13
198.....	50	1.8	7.6	.....	.....	1.5
245.....	50	7.0	6.0	54.0	15.7	3.18
248.....	50	0.9	6.6	55.3	14.9	0.02
250.....	100	3.4	6.2	54.2	15.0	0.05
252.....	100	2.0	6.0	54.7	15.9	0.03
252.....	50	4.1	4.8	.....	.....	0.72
253.....	50	2.0	6.0	54.6	16.3	0.11

Butadiene is converted almost exclusively to beta-butylenes in this process. Tests on the selective hydrogenation of isoprene and piperylene gave data showing that the hydrogen addition takes place predominantly in the 1,4 positions in these cases also.

Example III

A mixture of trimethylcyclohexadienes obtained by hydrogenating isophorone and dehydrating the resulting product and composed of approximately 75% of 1,1,3-trimethylcyclohexadiene-3,5 and 1,1,3-trimethylcyclohexadiene-2,4 and 25% of 1,1-dimethyl-3-methylenecyclohexene-4, was subjected to selective hydrogenation using a nickel sulfide catalyst prepared by reacting nickel oxide deposited on gamma alumina with hydrogen sulfide at 400° C. for four hours.

The hydrogenation was carried out using a pressure of 135 p. s. i. g., a liquid hourly space velocity of 0.5 and a molar ratio of hydrogen to hydrocarbon of 7.0 to 1. The product obtained from operating at 250° C. had the following properties:

Distillation range	Percent of total product	Bromine number
132-142° C	71	131
142-158° C	29	130
Higher boiling	Trace	.....

Since the bromine number of the feed was 260, these results show that the trimethyl cyclohexadienes were substantially completely converted to trimethylcyclohexenes under these conditions.

It will be seen that the invention offers many advantages particularly with respect to the selectivity of the hydrogenation and the efficiency of the conversions which may be obtained. The new process is also extremely useful and economical due to the freedom from side reactions and the long periods of operation between catalyst regenerations, which are most desirable industrially. While the treatment of conjugated diolefins has been emphasized in the foregoing examples, the process is equally applicable to the production of particular mono-olefins from other more highly unsaturated hydrocarbons, as shown by the following example:

Example IV

Limonene was selectively hydrogenated in the liquid phase using nickel sulfide supported on alumina as the catalyst. At a reaction temperature of 150° C. and a pressure of 1000 p. s. i. g. the hydrogenation proceeded at a fairly uniform rate until one mole of hydrogen per mole of limonene had been consumed after which the consumption of hydrogen ceased. Analysis

25 showed that the product contained only mono-olefins and that about 90% was methyl isopropyl cyclohexene.

In a companion run there was evidence that unsupported nickel sulfide was somewhat less 30 active as a catalyst but the hydrogenation was selective in this case also.

Other polyolefinic hydrocarbons which may be similarly converted to the corresponding mono-olefins are, for example, the hexadienes, isoprene, 35 piperylene, cyclohexadiene, methyl cyclohexadiene, dipentene, terpinene, etc. Compounds having an acetylenic group and an olefinic group in the molecule such as vinyl acetylene and the like may likewise be used as starting material for the preparation of mono-olefins according to the invention. The invention is not restricted to the treatment of hydrocarbons alone, but may be applied to the partial saturation of substitution 40 products thereof having a plurality of aliphatic unsaturated groups in the molecule, such, for example, as polyolefinic acids, alcohols, esters, ethers, ketones, aldehydes, amines, nitro compounds, halides, sulfides, mercaptans, etc. The substituent groups or elements present may be 45 inert under the reaction conditions or may be such as to undergo simultaneous change without interfering with the partial hydrogenation of the unsaturated bonds present. Thus, the invention may be advantageously used to reduce the unsaturation 50 of drying oils while avoiding formation of completely saturated products. Sorbic acid may be converted by the new process to the much more stable 3-hexenoic acid. Geraniol may be likewise treated to obtain the corresponding de-55 cylenol and isobutetyl isobutyl ketone may be produced from phorone. Butadienyl acetate, for example, is typical of another type of substituted starting material which may be used in the process. Aromatic or heterocyclic groups or both may 60 also be present in the feed material.

It is thus apparent that the invention is capable of wide variation not only with respect to the 65 compounds which may be selectively hydrogenated and the reaction conditions which may be used but also in regard to the methods of operation which may be used. Thus, while continuous 70 operation has been emphasized as the preferred procedure, the new process may also be carried out intermittently or batchwise. Where the selective 75 hydrogenation is to be carried out with the

material to be hydrogenated in the liquid phase, it is often advantageous to employ solvents or diluents, especially with starting materials of high volatility as the operating pressure may be thereby reduced. Still other variations in the process may be made and it will be evident that the invention is not limited to the details described by way of illustration nor by any theory proposed in explanation of the improved results obtained.

We claim as our invention:

1. A process for producing a mono-olefinic compound from the corresponding diolefinic compound to the substantial exclusion of the corresponding saturated product of hydrogenation which comprises reacting said diolefinic compound with hydrogen in the presence of nickel sulfide.

2. A process for substantially completely converting a diolefin to the corresponding mono-olefin without appreciable formation of saturated carbon compounds which comprises reacting said diolefin with hydrogen in the presence of nickel sulfide.

3. A process for producing a mono-olefin from a diolefin to the substantial exclusion of the corresponding saturated product of hydrogenation which comprises reacting said diolefin with hydrogen in the presence of a nickel sulfide catalyst and removing reacted hydrocarbon from the reaction zone substantially as fast as one molecule of hydrogen per molecule of diolefin is reacted therewith thereby obtaining a mono-olefin substantially devoid of paraffins.

4. A process for converting a mixture of mono- and diolefins predominating in mono-olefins substantially to mono-olefin which comprises con-

tacting said mixture and a substantial molar excess of hydrogen based on said diolefin with nickel sulfide under hydrogenating conditions and removing reacted hydrocarbon from the reaction zone after reaction of one molecule of hydrogen per molecule of diolefin thereby to convert said diolefins to the corresponding mono-olefins without appreciable formation of any saturated compounds.

10 5. A process of producing 2-butylene from butadiene which comprises passing butadiene together with at least five mols of hydrogen per mol of diolefin present over a nickel sulfide catalyst at between about 100 and about 400° C. at a liquid hourly space velocity of about 0.5 to 12 thereby to produce 2-butylene without appreciable production of butane.

20 6. A process of producing amylenes from the corresponding pentadienes which comprises contacting said pentadienes and a substantial molar excess of hydrogen with a nickel sulfide catalyst at temperatures between about 100 and about 400° C. thereby to produce amylenes without appreciable production of pentanes.

25 7. A process for producing a mono-olefinic compound to the substantial exclusion of its corresponding saturated product of hydrogenation which comprises reacting an unsaturated compound having at least four unsaturated carbon atoms in a non-aromatic group with hydrogen under the catalytic influence of a catalyst having an active surface predominating in nickel sulfide thereby to produce a corresponding mono-olefinic compound to the substantial exclusion of the corresponding saturated product of hydrogenation.
